[57] CLAIM

The ornamental design for a tether restrainer device or similar article, as shown and described.

DESCRIPTION

FIG. 1 is a left side, top and front perspective view of a tether restrainer device or similar article showing my new design;

FIG. 2 is a front elevational view thereof;

FIG. 3 is a right side elevational view thereof, the side opposite being a mirror image; and,

FIG. 4 is a top plan view thereof, the bottom plan view being a mirror image.

FIG. 1.

FIG. 2.

FIG. 3.

FIG. 4.
